UNITED STATES PATENT OFFICE

HIRAM HAVENS, OF HARTFORD, CONNECTICUT.

IMPROVEMENT IN TAIL-BOARD CATCHES FOR WAGONS.

Specification forming part of Letters Patent No. **222,397**, dated December 9, 1879; application filed October 24, 1879.

To all whom it may concern:

Be it known that I, HIRAM HAVENS, of Hartford, in the county of Hartford and State of Connecticut, have invented certain new and useful Improvements in Tail-Board Catches for Wagons; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvement relates to catches for holding up the tail-board of wagons. As commonly constructed these consist of hasps or latches attached by a spring to the side-boards of the wagon-body, which enter into recesses or loops in the tail-board, and which are ordinarily difficult to operate or open.

My improvement has for its object the furnishing of a catch which shall be more secure and durable than those heretofore employed, as well as being more easily operated.

My invention consists in the construction and arrangement of parts, as will be herein-after described.

In the accompanying drawings, Figure 1 shows a top view of my improved catch as applied to one end of the tail-board of a wagon, with the top side of the box containing the spring removed, so as to show the interior parts. Fig. 2 shows a view from the rear of the wagon. Fig. 3 shows a side view of the part attached to the tail-board.

A shows part of the side of a wagon-body. B shows the end of the tail-board as it is turned up and rests against the side. C is a box, consisting of two sides and a bottom, formed of cast-iron or other suitable material, which is attached to the end of the tail-board by screws or bolts, as shown in the drawings. D is a bent lever turning upon the pivot-pin E, which passes through the sides of the box C. This lever has at its forward end the hook D', and at the opposite end it bends around the back of the tail-board and lies just within the

sides of the box C, forming a thumb-latch, H, by the pressing of which the hook D' is forced outward. F is a spring, attached to the bottom of the box C at one end, and operating outward at the other upon the arm of the lever D, which forms the thumb-latch. G is a piece attached to the outside of the side of the wagon-body by screws or otherwise, as shown in the drawings. It is furnished with the hook G', which engages the hook D' when the tail-board is raised, as in the position shown. The parts D and G can be made of cast or malleable iron, or of any suitable metal.

The operation of my invention is as follows: In the position shown in the drawings the tail-board is raised and hooked. When it is desired to let it down the top is held by the hands and the two thumbs pressed upon the latches H. This releases the hooks, and the hands carry the tail-board down. When the tail-board is raised the hooking is automatic. On being pressed into its proper position the hooks engage and hold it in place.

The advantages of my improved catch are: It is out of the way of anything placed upon the top of the sides; it is not in danger of being accidentally released; it is stronger and more secure than those in ordinary use; it can be easily and readily operated to let down the tail-board when desired, and can readily be attached to wagons as ordinarily constructed.

What I claim as my invention is—

1. The combination of the box C, the lever D, with its hook D' and thumb-latch H, the spring F, and the plate G, with its hook G', substantially as described.
2. The combination, with a wagon-body, of the spring-hook D, provided with a thumb-latch, H, attached to the tail-board, and the hooked plate G, attached to the side, substantially as described.

HIRAM HAVENS.
